(57) **CLAIM**

The ornamental design for a portion of a display panel with an animated computer icon, substantially as shown and described.

DESCRIPTION

FIG. 1 is a front view of a first image in a sequence for a portion of a display panel with an animated computer icon, showing my new design;

FIG. 2 is a front view of a second image thereof;

FIG. 3 is a front view of a third image thereof; and,

FIG. 4 is a front view of a fourth image thereof.

The appearance of the transitional image sequentially transitions between the images shown in FIGS. 1-4. The process or period in which one image transitions to another image forms no part of the claimed design.

The broken line bordering each figure and illustrating the display panel portion forms no part of the claimed design. The broken lines within each figure illustrate portions of the animated computer icon that form no part of the claimed design.
